UNITED STATES PATENT OFFICE.

MAX JAEGER, OF MOUNT VERNON, NEW YORK.

MECHANICAL LUBRICATOR.

1,119,607.

Specification of Letters Patent.

Patented Dec. 1, 1914.

Application filed September 17, 1913. Serial No. 790,211.

To all whom it may concern:

Be it known that I, MAX JAEGER, a citizen of the United States, and a resident of Mount Vernon, in the county of Westchester 5 and State of New York, have invented a new and Improved Mechanical Lubricator, of which the following is a full, clear, and exact description.

This invention relates to lubricators, and 10 has for an object to provide an improved structure which may be continuously operated and caused to feed any desired quantity of oil either continuously or intermittently to an article or piece of machinery being lubricated.

Another object of the invention is to provide a small, strong, lubricating device which may be adjusted at any time for 15 varying the amount of oil used, said adjustment being designed to be adjusted while the device is running or while it is stationary.

A further object of the invention is to provide a lubricating device or pump which 20 draws from the tank a continuous, substantially even supply of oil and forces the same out through one or more discharge openings, one of the discharge openings being a return to the tank, and the other one or more discharge openings being to the engine or various devices being lubricated, the adjustment of the various parts of the pump being such as to cause any portion of the oil drawn from the tank to be returned to the 25 tank, the remaining part being dispensed or fed to the engine or other articles being lubricated.

A still further object of the invention is to provide a pump which may be variously 30 adjusted so that it will continuously draw an even supply of oil from the supply tank and discharge any portion thereof back into the tank, and any desired proportion to the engine or other device being lubricated, the 35 discharged portion of the liquid being adapted to be fed either in a continuous stream by a proper adjustment of the pump or intermittently by a proper adjustment of the pump.

50 In carrying out the objects of the invention the pump may be made of any desired size, and may be connected up in any desired manner to a power mechanism, as for instance to an engine being lubricated. 55 It will also be evident that the various castings may be made in a number of different

parts or cast in a comparatively few parts, as may seem more desirable to the particular use to which any particular pump is used.

In forming the pump a base is provided carrying a chamber in which a piston is rotatably mounted, the piston being adapted to draw oil from a suitable opening or port and force the oil through the discharge 60 opening or port. The oil discharged from the chamber passes through a controlling mechanism, preferably mounted on the chamber and arranged to control the discharge in several ways. For instance, the 65 discharge could be caused to divide and half go back to the tank from which it is drawn and the other half discharged in a continuous stream to the engine. If this arrangement was not desired, but an intermittent 70 arrangement was desired, certain of the parts could be adjusted so as to intermittently discharge any proportion of the fluid forced from the chamber. The adjustment 75 of the continuous flow of lubricant to the 80 engine is controlled or regulated by a sliding bar or plunger which acts in the capacity of a valve, and which may be adjusted so as to provide any desired opening or adjustment of this valve or plunger, automatically adjusting a second valve or plunger 85 which controls the return flow from the cylinder to the tank so that what oil is not forced to the engine is forced back to the tank, whereby none of the oil is wasted and 90 any desired quantity may be properly used. When it is desired that the feed to the engine should be intermittent a cam connected 95 with the shaft on which the piston is mounted is caused to engage a suitable mechanism for operating a spring pressed slide. This slide is designed to engage an adjustable screw movable with the plunger or valve for controlling the discharge opening to the engine, whereby when the cam is operated and the set screw is moved the valve or plunger 100 will be operated for opening temporarily the discharge to the engine. The time that the intermittent discharge is flowing is determined by the length of the face of the cam which of course may be any desired 105 length.

In the accompanying drawings:—Figure 1 is a side view of a pump and valve mechanism disclosing an embodiment of the invention; Fig. 2 is a top plan view of the structure shown in Fig. 1; Fig. 3 is a longi-

tudinal vertical section through the structure shown in Fig. 1; Fig. 4 is a section through Fig. 3 approximately on line 4—4; Fig. 5 is a detailed perspective view of the 5 valve plunger controlling the return flow of oil, the same being associated with one of the end castings.

Referring to the accompanying drawings by numeral 1 indicates a base on which is 10 mounted a casing 2 formed with a chamber 3, the casing 2 being preferably cast integral with base 1 though not necessarily so. A suitable face plate 4 is provided for casing 2 which is bolted or secured in place in any 15 desired manner, whereby piston 5 is properly inclosed, and whereby the chamber 3 is formed substantially air-tight. The casing 2 is provided with an inlet opening 6 and an outlet opening 7, inlet opening 6 20 having gouged-out portions 6' and 8 to allow the fluid to freely flow into the casing, and outlet 7 having a gouged-out portion 9 for allowing the free flow of the fluid to outlet 7. It will be observed that the piston 5 is 25 arranged eccentric to the chamber 3 so as to provide a proper action for the blades 10 and 11. It will be noted that the blades 10 and 11 extend past the center of the piston and almost entirely across the piston, whereby 30 an ample bearing surface for each blade is provided, and also ample room for the springs 12 and 13. In operation the piston 5 is designed to rotate in the direction of the arrow shown in Fig. 3, and to draw in lubricant from any suitable tank through port 6 and force said lubricant out through port 7. The piston 5 is designed to operate continuously, and to cause the lubricant to flow as 35 before stated, the piston 5 being operated by 40 a shaft 14 which in turn is connected to the engine or other source of power by any desired means.

In connection with shaft 14 it will be observed that the same is journaled in the 45 boss 15 of casing 2, and also journaled in the boss 16 of standard 17, which standard is bolted or otherwise rigidly secured to base 1, though if desired this standard could be cast integral with base 1. Standard 17 extends above shaft 14, and is provided with a bearing portion 18, in which a journal pin 19 is arranged. Journal pin 19 has mounted thereon a lever 20 provided with arms 21 and 22, arm 22 carrying an anti-friction 50 roller 23 bearing on cam 24, while arm 21 is provided with a friction face or shoulder 25 bearing against the flanged roller 26. Cam 24 is rigidly secured to shaft 14 and is rotatable therewith, so that upon each rotation of shaft 14 the cam will operate the 55 lever 20 for moving arm 21. The friction head or shoulder 25 on arm 21 overlaps the flange 27 on the roller 26 so that the roller 26 is properly held on its stub shaft 28 with- 60 out any additional securing means. The 65

stub shaft 28 is rigidly secured to the slide 29 which is slidably mounted in suitable ways 30 (Fig. 4). Slide 29 has a contact extension 31 at one end and a spring receiving extension 32 at the opposite end, extension 32 being formed with a head 33 so that spring 34 will press against head 33 and against the housing 35 of the discharge controlling mechanism. The spring 34 normally holds slide 29 substantially in the 70 position shown in Fig. 1, but permits the slide to be moved therefrom whenever cam 24 operates lever 20. If the set screw 36 is in substantially the position shown in Fig. 1 the movement of slide 29 will have no effect, 75 but if set screw 36 is adjusted until the end 37 is adjacent end 31 the slide 29 will force set screw 36 and the various parts connected therewith into longitudinal movement so as to intermittently open the discharge to the 80 engine.

Housing 35 may be connected with casing 2 in any desired manner, as for instance by being threaded thereon, as shown in Fig. 3. This housing is provided with a discharge 90 opening 38 through which all of the discharge from the discharge port 7 passes. Part of the oil discharged into passageway 38 may pass through the discharge opening 39, and part through the discharge opening 95 40. The opening 39 leads back to the tank from which the lubricant is drawn, while the opening 40 leads to the engine or other article being lubricated. The housing 35 is provided with a bore 41 in which a valve 100 plunger 42 is slidably mounted. The valve plunger 42 is provided with an enlargement 47 at one end which operates in bore 44 in the end casting 45. A spring 43 presses against head 47, and against the shoulder 49 105 formed at the juncture of bore 44 and bore 41 so that spring 43 will give the valve plunger 42 a continuous tendency to move toward the set screw 46. Set screw 46 may be adjusted to any desired extent for moving or adjusting the valve plunger 42 against the action of spring 43. Lock nut 48 is used for locking set screw 46 in any of its adjusted positions. The valve plunger 42 is provided with a passageway 50 which 110 may be caused to register with the passageway 38 and discharge opening 40, or may be caused to only partially register therewith. When passageway 50 is registering with passageway 38 and discharge opening 40 all 115 of the lubricant passing through cylinder 3 is discharged out the discharge opening 40. When it is desired to reduce the amount of lubricant fed to the engine set screw 46 is adjusted until the spring moves the valve 120 plunger 42 to the desired extent, as for instance, to the position shown in Fig. 3, wherein approximately half of the lubricant pumped will pass out discharge opening 40, and the other half will pass back to the 125 130

tank through the discharge port or opening 39. By adjusting set screw 46 back and forth as desired, any desired quantity of lubricant may be fed to the engine up to the 5 full limit of the device, the proportion of lubricant not fed to the engine returning to the tank. The adjustment of set screw 46 may be made at any time, either when the device is standing still or while it is operating.

Slidely mounted upon the end 51 of housing 35 is a casting 52, which carries lugs 53 and 54, lug 54 accommodating the set screw 36, heretofore described, and lug 53 15 accommodating an auxiliary valve plunger 55. The auxiliary valve plunger 55 is preferably reduced at one end for providing a pin 57 which projects through the lug 53, and which carries a suitable lock nut 58 for 20 holding member 55 in place. As clearly shown in Fig. 5 the auxiliary valve plunger 55 is provided with an elongated aperture 59 which is rounded at each end, and at one end is filled by a pin 60, which may be held 25 in place in any desired manner, as for instance by a suitable retaining screw 61. The valve plunger 55 fits into a suitable bore 62 (Fig. 4) and is of such length that the plug 60 will be substantially in line with passage- 30 way 50 so that as passageway 50 uncovers the passageway 38 so as to allow the lubricant to pass to the discharge opening 40 pin 60 will cover the port or opening 39 to the same extent so that the correct proportion 35 of lubricant will be shut off from returning to the tank. When port 50 is in complete alinement with passageway 38 the plug or pin 60 will completely inclose the opening 39 so that there will be no return of any of the 40 lubricant to the tank. In order that the relation of the plug 60 and passageway 50 may be known an aperture 63 (Fig. 3) is provided in the end casting 52, and a depression 64 is provided in housing 35 so that the 45 depression 64 and aperture 63 register it will be known that the passageway 50 is registering with passageway 38. In order to prevent any rotation of the valve plunger 42 a pin or lug 65 is provided, as 50 shown in Fig. 3, which is adapted to fit into a notch 66 (Fig. 5) in the end casting 52, which end casting cannot rotate as the same is connected with the auxiliary valve plunger 55.

In operating the device the same is connected to any desired tank or reservoir by pipe 67 so that the lubricant may flow from the tank or reservoir into the chamber 3 and be forced therefrom as above described. 55 As the fluid passes through passageway 38 it is divided and goes through the discharge opening 40 and from thence through pipe 68 to the engine, and the other part goes through discharge opening 39 to pipe 69 60 and from thence back to the tank or reser-

voir, this distribution taking place provided passageway 50 is only partially in registry with passageway 38. As passageway 50 is adjusted back and forth so as to more or less register with passageway 38 the lug or 65 member 60 is also adjusted back and forth simultaneously therewith so as to cover and uncover opening 39. By simultaneously moving the members 42 and 55 which movement may be gaged by aperture 63 any desired proportion of the fluid pumped may be caused to flow to the engine and the remaining part returned to the tank. By operating the member 42 through the adjustment of set screw 46 a continuous flow of 70 lubricant is provided to the engine. However, if an intermittent flow or feed is desired set screw 46 is moved backward or adjusted so as to allow spring 43 to cause passageway 50 to be out of registry with 75 passageway 38. Set screw 36 is then adjusted to be more or less in the path of movement of slide 29. The operation of cam 24 will cause the slide 29 to be moved and consequently to engage the contact point 37 of 80 set screw 36, and thereby move the end casting 52. As end casting 52 is moved the same will move the valve plunger 42 and cause the same to be positioned so that the passageway 50 will temporarily register to 85 a greater or less extent with passageway 38, the amount of registry of these passageways corresponding to the amount of adjustment of set screw 36. It will be noted from Fig. 90 3 that the plunger valve 42 is securely fastened to the end casting 52 by suitable clamping nuts 70 which rigidly hold the two parts together. As shown in Fig. 1 cam 24 is provided with a small rounded end so that the passageways 50 and 38 are caused 95 to register or partially register only for an instant and then to move out of registry. If the end of cam 24 was broadened so as to present an appreciable amount of a circle the passageways 50 and 38 would remain in 100 registry a corresponding greater length of time. It will be evident that the shaft 14 could be connected with the engine so as to properly time the discharge of the lubricant when the same is discharged intermittently, 105 this action, however, not forming any part 110 of the invention.

Having thus described my invention I claim as new and desire to secure by Letters Patent, the following—

1. In a lubricating device of the character described, a continuously operating pump, a valve mechanism for controlling the output of said pump, said valve mechanism having a plurality of discharge openings, 115 and means for adjusting said valve mechanism so as to open one discharge opening and close the other, the movement being such that one opening is being opened in the same proportion as the other is closed. 120

2. In a lubricator of the class described, a continuously operating pump, a pair of discharge members associated with said pump, each of said discharge members being of a size to accommodate the entire discharge from the pump, a pair of valve plungers controlling said discharge members, and means for adjusting the position of said plungers so that when one of the plungers 10 is closing its discharge member the other plunger is opening its discharge member, whereby any proportion of the discharge from said pump may be forced out either of said discharge members.

15 3. In a lubricator of the class described, a pump, a pair of discharge members in said pump, one of said discharge members leading to the article to be lubricated and the other of said discharge members leading to 20 the supply tank from which said pump draws its lubricant, a reciprocating valve plunger for controlling the opening of each of said discharge members, said valve members being arranged in such relationship to 25 each other that when one discharge member is opened the other discharge member is closed, manually adjusted means for moving said valve plungers in one direction, and automatic means for moving said valve 30 plungers in the opposite direction.

4. In a lubricator of the class described, a continuously operated pump designed to draw in an even supply of lubricant and discharge an even quantity of lubricant, and means connected with a discharge opening 35 of said pump for directing any desired proportion of said discharge back to the supply tank, and any desired proportion of lubricant to the article being lubricated, said 40 means including a valve member adapted to close the discharge leading back to the supply tank in proportion to the opening of the discharge leading to the article to be lubricated.

45 5. In a lubricator of the class described, a pump adapted to provide a continuous stream, and means connected with said pump for dividing said stream between a return discharge member and a member extending 50 to the article being lubricated, said means including a reciprocating valve member for each of the discharge members, a connecting member for rigidly connecting together said reciprocating members, a 55 spring acting on said reciprocating members for giving the same a continual tendency to remain in one position and return to that position when moved therefrom, and a manually adjustable member acting on 60 said reciprocating members for moving the same against the action of said spring.

6. A lubricator comprising a pump adapted 65 to draw lubricant from a supply tank and force the same in a continuous stream through a discharge opening, and means

connected with said discharge opening for distributing the discharge from said pump, said means comprising a return pipe connected with said supply tank, a distributing member connected with the article being lubricated, a valve member arranged to control the flow of fluid through said distributing member, a valve member arranged to control the flow of fluid through said return pipe, and means for causing one of 70 said valve members to close as the other is opened, whereby any proportion of the lubricant may be fed to the article being lubricated and the remaining part returned to the supply tank.

7. A lubricator comprising means for directing a continuous flow of lubricant through a discharge pipe, and means connected with said discharge pipe for distributing the lubricant therefrom, said means comprising a return pipe for returning the lubricant to said first mentioned means, a distributing pipe for distributing lubricant to an article, both of said pipes being in free communication with said discharge pipe, a reciprocating member intersecting said distributing pipe, a second reciprocating member intersecting said return pipe, each of said reciprocating members being provided with an aperture, said apertures being arranged to register with said discharge pipe at different times, and means for adjusting said reciprocating members so that as one of the same moves out of registry with the discharge pipe the other will move into registry therewith, whereby the proportion of lubricant from said discharge pipe to the distributing pipe and return pipe may be varied.

8. A lubricator comprising a pump connected with a suitable supply and adapted to continuously force a certain sized stream of lubricant through a discharge opening, and means connected with said discharge opening for distributing said stream of lubricant, said means comprising a housing having a main passageway therethrough and an auxiliary passageway extending at an angle to said main passageway, a distributing member connected with 110 said main passageway for distributing the lubricant to an article, a return pipe connected with said auxiliary passageway for returning lubricant to the supply tank from which said pump is supplied, a valve arranged in said main passageway for controlling the flow of lubricant to said distributing pipe, a valve arranged in said auxiliary passageway for controlling the flow of lubricant to said return pipe, means 115 for rigidly connecting said valves together, said valves being set so that one valve will be closing as the other is opening, means for moving said valves so that the valve controlling the return pipe will be main- 120

125

tained open, and manually operated means for opening and maintaining open the valve controlling the discharge through the distributing pipe.

9. A lubricator comprising a continuously operating pump adapted to draw from a supply of lubricant, and force the same in a continuous stream through a discharge opening, and means for distributing the stream of lubricant forced through said discharge opening, said means including a main discharge passageway, an auxiliary discharge passageway, a distributing pipe connected with said main discharge passageway, a return pipe connected with said auxiliary discharge passageway for returning lubricant to said supply tank, a valve member intersecting each of said passageways controlling the flow of lubricant therethrough, means connecting said valve members so that when one is closed the other will be opened and vice versa, means for resiliently holding the valve member in the main discharge passageway closed and the valve member in the auxiliary passageway open, and intermittently operated means connected with the shaft of said pump for intermittently opening said valve member in said main passageway and closing said valve member in said auxiliary passageway, whereby lubricant is intermittently fed to said article through said distributing pipe.
10. A lubricator comprising a continu-

ously operated pump designed to draw lubricant from a suitable supply tank and force the same in a continuous stream out a discharge opening, means for distributing the lubricant forced out said discharge opening, said means including a distributing pipe for distributing lubricant to an article, and a return pipe for returning the lubricant to said supply tank, a valve member interposed in each of said pipes controlling the flow of fluid therethrough, means for normally holding said valve members in such a position as to cause lubricant to pass through said distributing pipe and prevent all of said lubricant from passing through said return pipe, a slide adapted to operate said valve members for opening the distributing pipe and closing the return pipe, a pivotally mounted member for actuating said slide, and a cam connected with said pump and continuously operated thereby for actuating said pivotally mounted member, whereby said pivotally mounted member is intermittently actuated and the discharge through said distributing pipe is intermittent.

In testimony whereof I have signed my name to this specification in the presence of two subscribing witnesses.

MAX JAEGER.
